UNITED STATES PATENT OFFICE

155,129

DESIGN FOR A PENCIL SHARPENER

Ladislav Degefors, Solna, Sweden, assignor to
Instrumentaktiebolaget J. A. Palm, Stockholm,
Sweden

Application April 23, 1947, Serial No. 138,550
In Sweden April 10, 1947

Term of patent 14 years

(Cl. D74—1)

To all whom it may concern:

Be it known that I, Ladislav Degefors, a subject of the King of Sweden, residing at Solna, Sweden, have invented a new, original, and ornamental Design for Pencil Sharpeners, of which the following is a specification, reference being had to the accompanying drawing, forming part thereof.

In the drawing,

Fig. 1 is a perspective view of the pencil sharpener, showing my new design;

Fig. 2 is a perspective view thereof from a different angle;

Fig. 3 is an end view, viewed from the right of Fig. 1.

I claim:

The ornamental design for a pencil sharpener, as shown.

LADISLAV DEGEFORS.
